UNITED STATES PATENT OFFICE.

JOHN EDWIN LONG, OF HAVELOCK, NEBRASKA.

DIRT-LOADING MACHINE.

1,380,488.

Specification of Letters Patent. Patented June 7, 1921.

Application filed May 9, 1919. Serial No. 295,930.

To all whom it may concern:

Be it known that I, JOHN E. LONG, a citizen of the United States, residing at Havelock, in the county of Lancaster and State 5 of Nebraska, have invented a new and useful Dirt-Loading Machine, of which the following is a specification.

This invention relates to improvements in machines for loading wagons and the like with dirt or other material placed in the machine, one of the objects of the invention being to provide novel means whereby the dirt or other material is elevated from an excavation into a receptacle for delivering the material into wagons, cars or the like, the present invention being an improvement on that shown and described in the patent issued to me on July 6, 1915, No. 1,145,379.

A further object of the invention is the 10 provision of improved means for elevating the platform of the machine from an excavation into position for delivering the material into the hopper.

A further object of the invention is the 15 provision of means for facilitating the turning of the machine when moving it.

With the foregoing and other objects in view, which will appear as the description proceeds, the invention consists in the novel 20 features of construction and combination of parts which will be more fully described hereinafter and particularly pointed out in the claims.

In the drawings accompanying and forming 25 part of this specification,

Figure 1 is a side elevation of the machine showing the loading platform in its lowered position;

Fig. 2 is a plan view thereof; and

Fig. 3 is a sectional elevation showing 30 the platform in elevated position.

The same characters of reference designate the same parts in the different figures of the drawings.

Referring to the drawings, 2 designates a 35 frame or truck carrying an axle 3, which is supported by wheels 4, and on which frame are mounted standards 5 having suitable braces 6, the standards being connected at 40 their upper ends by a cross beam 7, on the end portions of which are secured the front ends of downwardly and rearwardly inclined side beams 8. The side beams are supported at their rear ends by a cross beam 50 9, to which are attached a pair of standards 55 10, the standards being connected together

at their lower ends by a second cross beam 11, the standards and cross beams 9 and 11 thus forming a rear frame for supporting the rear ends of the side beams 8. The side 60 beams 8 are further connected to the standards 10 by means of a pair of brace members or stays 12.

For facilitating the turning of the machine, I have provided a rear truck, formed 65 of a cross beam 13 carrying an axle 14 and a pair of wheels or rollers 15. This truck is pivotally connected to the rear frame by means of a king bolt 16 passing through the lower cross beam 11 and the truck beam 70 13. From this construction it will be seen that the truck may be turned in any direction, whereby it is considerably easier to guide the machine in any desired direction than if mounted on a rigid truck. Suitable 75 means may be secured to the cross beam 13 for hauling the machine. This means may consist of a flexible member 17 of loop form, as shown, for manually hauling the machine, or a suitable draft tongue may be secured to the beam for permitting horses to 80 be hitched thereto.

A hopper 18 is fixedly mounted between the front end portions of the side beams 8 and has its bottom inclined downwardly and 85 rearwardly. The hopper is further supported by means of a pair of inclined members 19 secured to the beams 8 and connected together at their upper and lower ends by a pair of cross beams 20. The hopper 90 is open at the top and front thereof, and adjacent its rear end is provided with inclined guide cleats 21 secured to the side walls and which are adapted to receive and 95 guide a gate 22 that can be adjusted vertically by means of a cord 23 attached to the upper edge of the gate and passing over a pulley 24 mounted on a cross bar 25 secured at the upper ends of the guide cleats 21. By the provision of this gate an opening of any 100 desired height may be formed between the lower edge of the gate and the bottom of the hopper, whereby the amount of material supplied to the delivery end of the hopper can be controlled. Secured to the rear end 105 of the hopper, approximately at the middle of its height, is a cross beam 26, to which is hingedly secured an end gate 27 adapted to to close the lower end of the hopper, and which gate opens outwardly. For operating 110 27, I have provided a lever mechanism, which comprises a cross bar 28 secured

at its ends to the stays 12, on which cross bar is pivotally mounted a lever 29 having pivot-
ed at its inner end a pair of links 30 secured
at their opposite ends to the lower portion
5 of the gate 27. The lever 29 may be pro-
vided at its outer end with a flexible operat-
ing cord 31, whereby on pulling said cord
downwardly the lever will operate to open
10 the gate, as shown in Fig. 3, and when it is
desired to hold the gate closed the cord 31
may be secured around the cross beam 9,
thereby holding the outer end of the lever
elevated, the rigid members 30 thus bearing
15 against the lower edge of the gate and holding
the same closed.

For facilitating the delivery of material
from the hopper, I have provided an endless
apron adapted to travel on rollers 32
20 mounted in bearings at the upper and lower
ends of the bottom of the hopper, and which
apron is formed of a plurality of slats 33
flexibly connected together, whereby the
apron is adapted to travel around the bot-
25 tom of the hopper, as clearly shown in Fig.
3. By the provision of this apron the dirt
or other material in the hopper will be
caused to quickly gravitate to the lower end
of the hopper, as the weight of such mate-
30 rial will cause the apron to travel on the
rollers 32.

For the purpose of holding the front
frame 2 fixed relatively to the side beams 8,
a pair of strips 34 are secured at one end to
the standards 5 and at their opposite ends
35 to the sides of the hopper. A pair of side
arms 35 are pivotally mounted at one end
thereof on the ends of the axle 3, and are
secured together near their opposite ends
by a cross strip 36. The arms 35 carry at
40 their free ends a pair of bearings 37 in
which is mounted a rockable shaft 38, to one
side of which is secured a rearwardly ex-
tending member 39 having secured at its
rear end a cross strip 40. Secured beneath
45 the member 39 at the pivotal end thereof, is
a spacing member 41, which is suitably
braced by a stay 42 secured at one end to
the spacing member 41 and at its opposite
end to the member 39. To the lower end
50 of the spacing member 41 is rigidly secured
a loading platform 43, which is provided
with a back wall 44 adapted to receive the
dirt when the platform is swung upwardly
as hereinafter described. Carried by the
55 truck 2 approximately centrally of its
width, is a lengthwise extending member 45,
provided near its front end with an aper-
ture in which are pivoted the lower ends
of a pair of upright rocking members 46,
60 these members carrying between them at
their upper ends a suitable pulley 47. A
pair of stays 48 are pivotally secured at
their lower ends one at each side of the
truck 2 and brought together at their upper
65 ends and pivotally connected with support-

ing strips 49, one at each side thereof and
one between the stays 48. The strips 49
extend backwardly, the two outer strips
straddling the rocking members 46 and the
center strip passing between such rocking 70
members, the strips having a pair of rollers
50 secured between their ends back of the
upright rocking members 46. The upper
ends of the stays 48 are connected by a pair
of brace members 51, preferably of sheet 75
metal, the opposite ends of which are se-
cured to the rocking shaft 38, whereby the
shaft will be permitted to rock slightly in
its bearings. A rearwardly extending beam
52 secured to the truck 2 and provided with 80
a pair of upstanding perforated ears or lugs
53 provides a support for a pulley 54,
through which passes a rope or cable 55,
said cable passing over the pulley 47 and
back over the rollers 50 and secured at its 85
end to the truck 2 in any suitable manner.
By means of this cable the platform may
be raised or lowered and may be held in
elevated position by securing the end of
the cable to one of the upright members 10. 90
A pair of projecting members 56 are se-
cured to the uprights or standards 5 and are
adapted to contact with the cross strip 40
carried by the member 39, when the plat-
form is elevated to its highest position, 95
whereby the shaft 38 is rocked in its bear-
ings and the platform tipped backward, as
shown in Fig. 3, thereby to deliver its load
of material to the hopper.

From the foregoing it will be seen that 100
by reason of the fact that the platform is
spaced away from its supporting beams it
can be lowered below the surface to receive
dirt from an excavation, and that when it
is pulled up to its discharging position by 105
means of the cable 55 it will discharge its
load of material into the hopper, whereupon
the weight of the material will cause the
apron to travel around on the rollers and
deliver the material at the lower end of the 110
hopper, and when the car or wagon is in
proper position below such hopper the
hinged gate thereof may be operated by
pulling the cord 31 thereby to swing the
lever 29 into position to open the gate. 115

While I have described in detail the struc-
ture herein illustrated, it is to be under-
stood that I do not thereby limit my inven-
tion to the precise features of construction
shown, as I am aware that many mechani- 120
cal changes and modifications may be made
therein without departing from the spirit
and scope of the invention as set forth in
the appended claims.

Having thus described my invention, what 125
I claim is:

1. In a device of the class described, a
first frame; a hopper mounted on the frame;
a belt conveyer forming a bottom for the
hopper; a second frame pivoted to the first 130

frame for vertical swinging movement; a platform on the second frame and discharging on the conveyer in the general direction of travel of the conveyer when the second frame is swung upwardly and rearwardly; means for swinging the second frame upwardly and rearwardly; and means for stopping the upward and rearward movement of the second frame whereby the material on the platform will be discharged on the conveyer and facilitate the movement of the conveyer.

2. In a device of the class described, a first frame; a second frame pivoted to the first frame for vertical swinging movement; a rocking member pivoted at its lower end to the first frame; means coöperating with the upper end of the rocking member for swinging the rocking member rearwardly; a forwardly inclined stay pivoted at its lower end to the first frame; a rearwardly inclined connection between the upper end of the stay and the forward portion of the second frame; a supporting strip pivotally mounted on the stay adjacent to the upper end thereof and extended rearwardly therefrom; a roller on the rear end of the supporting strip and slidably engaged with the rocking member; a platform carried by the second frame; and means on the first frame for receiving material from the platform

when the second frame is swung upwardly and rearwardly.

3. In a device of the class described, a first frame; a second frame pivoted to the first frame for vertical swinging movement; a shaft mounted to rock in the second frame; a platform and means for mounting the platform on the shaft; a rocking member pivoted at its lower end to the first frame; means coöperating with the upper end of the rocking member for swinging the rocking member rearwardly; a forwardly inclined stay pivoted at its lower end to the first frame; a flexible element extended between the shaft and the stay; a supporting strip pivotally mounted on the stay adjacent to the upper end thereof and extended rearwardly therefrom, the rear end of the supporting strip being engaged slidably with the rocking member; and means on the first frame for receiving material from the platform when the second frame is swung upwardly and rearwardly.

In testimony that I claim the foregoing as my own, I have hereto affixed my signature in the presence of two witnesses.

JOHN EDWIN LONG.
